CLAIM

The ornamental design for an exit gate for dairy parlor, as shown and described.

DESCRIPTION

FIG. 1 is a perspective view of an exit gate for dairy parlor which shows my new design;

FIG. 2 is a rear elevational view thereof;

FIG. 3 is a side elevation thereof, the left side being a mirror image thereof;

FIG. 4 is a left-side sectional elevation taken along line 4—4 of FIG. 2; the right-side section being a mirror image thereof;

FIG. 5 is a front elevation thereof;

FIG. 6 is a bottom view thereof; and,

FIG. 7 is a top view thereof.
